CLAIM

The ornamental design for a ladder rack, as shown and described.

DESCRIPTION

FIG. 1 is a right front perspective view of a ladder rack according to our new design, showing front display panels opened laterally outwardly;

FIG. 2 is a left front perspective view thereof, the front display panels being folded inwardly;

FIG. 3 is a front elevational view of FIG. 2;

FIG. 4 is a rear elevational view of FIG. 2;

FIG. 5 is a top plan view of FIG. 2;

FIG. 6 is a side elevational view, from the left in FIG. 2;

FIG. 7 is a side elevational view, from the right in FIG. 2; and,

FIG. 8 is a bottom plan view of FIG. 2.

The pattern of circular apertures shown along part of the surface of the side panels in FIGS. 1, 2, 6 and 7 are understood to repeat uniformly along the entire surface of the side panels.
